UNITED STATES PATENT OFFICE.

ORMAN W. DICKERSON, OF OKLAHOMA CITY, OKLAHOMA.

TEMPER JACK FOR STANDARD CABLE TOOL AND PUMPING WELLS.

Application filed October 1, 1928. Serial No. 309,657.

My invention relates to temper jack for standard cable tool, for use in drilling oil and gas wells, and in pumping wells.

The objects of my invention are to provide 5 a device as described which will be new, novel, and of utility; which will be efficient for the purposes for which it is intended; which will save time; which will save the cable from the excessive wear caused by slipping through the 10 clamps; which will shift the load from one clamp to the other without stopping the drilling; which will fit either a right or left handed twist cable; which will prevent the cable from becoming untwisted and some of 15 its strands from bearing all the weight which should be carried by all of them together; which will equalize the weight carried, distributing it on the whole cable; which will permit of continuous drilling after the drilling 20 has been put in operation; which will allow the cable to be held firmly without the necessity of putting on it the extreme pressure which is now necessary; which will provide for greater and better gripping facilities of 25 the line, or cable; that will be efficient in use in pumping wells, and in raising or lowering quickly the pump rods therein; which will provide easy and quick means for raising and lowering pump rods in pumping 30 wells.

In the present manner of using temper screws each time the cable is slipped through the clamps, the wire line becomes worn to a certain extent and an amount of it is sliced off. After the rope slips through the clamps for a few feet the wire line has a tendency to follow the twist of the cable and for this reason will untwist the line and some of the strands so that the full weight of the drilling 35 tools will not draw it back in its proper position and such strands will remain loose and be subject to greater friction and wear than the others. One, or a few strands of the cable will have more tension than the 40 others and as a result the cable becomes irregular and out of shape and loses a large percentage of its strength. My device will obviate all of the above objections.

With these and other objects in view as will 45 more fully appear my invention consists in the construction, novel features, and combination of parts hereinafter more fully described, pointed out in the claims hereto appended, and illustrated in the accompanying 50 two-sheet drawing, of which,

Figure 1 is an elevational view of the

temper jack attached to fragment of walking beam; Fig. 2 is a perspective view of bushing blocks; Fig. 3 is a fragmentary sectional view showing jack raising means for 60 taper bar; Fig. 4 is a perspective view of one of the clamp slips; Fig. 5 is a perspective view of the bushing blocks and a fragment of taper bar; Fig. 6 is a sectional view along the line of 6—6 of Fig. 1; Fig. 7 is a front elevational 65 view of the temper jack showing the taper bar partly extended; Fig. 8 is a side elevational view of a temper jack showing the taper bar partly extended.

Like characters of reference designate like 70 parts in all the figures.

It is understood that various changes in the form, proportion, size, shape, weight and other details of construction, within the scope of my invention may be resorted to 75 without departing from the spirit or broad principle of my invention and without sacrificing any of the advantages thereof; also that the drawings are to be interpreted as being illustrative and not restrictive. 80

One embodiment of my invention is shown as follows: I show the ordinary parts of a standard drilling rig for the purposes of illustrating the application of my device such parts are the Sampson post 1, Sampson post 85 braces 2, 3, a walking beam 4, connecting therewith at 5, pulleys 6 and pulleys 7 for co-operatively holding a temper jack elevator rope 8, and a counterbalance weight 9 for balancing the weight of the taper bar and its 90 working parts. The duplicate pulleys and rope and weight on the opposite side of the Sampson post 1 and walking beam 4 are not shown in the drawing. I also show what is commonly called the head ache post 10, and a 95 telegraph wheel valve turn 11, and a reversing handle or rod 12 therefor. All of these parts have the usual uses for such parts. Adapted to depend from the walking beam 4 I provide a taper bar 13 being fastened at 14 100 to the said elevator rope 8 and balanced or supported by counterbalanced weight 9. A frame 15 is provided for housing the taper bar 13, and has an opening 16 therein; reins 17 and 18 are provided at its sides for guiding 105 and directing the movements of said taper bar; said taper bar 13 is wider at its top 19 than at its bottom 20 and the difference is gradual therebetween; it also is provided with a plurality of ratchet teeth, or steps, 21 110 for receiving and co-operating alternately with a pair of toothed dogs 22 and 23. I

provide holes 24 and 25 in said dogs for use in retiring said dogs from contacting said teeth 21 when so desired by co-operating with a holding means in like holes in the member 5 on which they are respectively pivoted at 26 and 27. Said dogs 22 and 23 are respectively actuated pivotally in holding position by springs 28 and 29. Said dogs are used as a jack for the purpose of stepping up, step by 10 step, the taper bar when desired, in lieu of the old fashioned screw method. A socket 30 with handle 31 therein is pivotal on pivot pin 32 and adapted to jack said dog 22 alternately moving holding dog 23.

15 Said frame 15 is provided at its lower end with a cross member 33 securely fastened thereto, having a lateral threaded perforation 34 in one side for receiving a similarly threaded member 35, said last named member 20 having a handle bar 36 on its outer end and a foot member 37 on its inner end for compressing and holding bushing blocks 38 and 39 against the side edges of said taper bar 13. Said bushing blocks each has an inside groove 25 40 for slidably fitting over the said edges of said taper bar 13, and one of them as shown at 41 on bushing block 39 has a rounded bulged outer side edge for preventing said blocks from lodging and sticking within the 30 reins 17 and 18 and for keeping said bushing blocks reasonably taut between said reins, and to enable the taper bar to pass up and down easily and follow its general taper. Said bushing blocks 38 and 39 may both be so 35 bulged if desired and they also have other grooves 42 and 43 for slidably fitting over the inside edges of cross member 33. The lower end 20 of said taper bar 13 is fitted with a head 44 rigidly held by said temper jack, 40 thereby preventing its turning, eliminating the jockey stick commonly used, and for suitably holding links 45 and 46, said links being adapted for holding clamp hooks 47 on which is suspended clamping member 48 and its accompanying and adjusting parts for gripping 45 said line or cable 49 at its lower gripping point. It is preferred in clamping member 48 to use the same form of clamps and slips with corrugations therein as is shown at 51, 50 52 and 53 in Fig. 4, and similar tightening and releasing means as are shown at 54, 58, 59, 60 and 61 as shown in Fig. 6.

I provide an upper line clamping means adjacent said socket 30 and handle member 31. 55 This comprises a thickened lower portion 59^a of rein 18 and a companion clamping member 61, both having a semi-circular recessed inside portion for holding slips 50 and 52, said slips having inside surface corrugations 51. Said 60 slips have a countersunk hole 53 in which to screw the slip against the side of said clamping members 59^a and 61. A bifurcated arm 54 is pivotally anchored at 55 on said cross-member 33 having a threaded perforation 56 in its central portion for receiving a simi-

larly threaded neck 57 having a turning handle 58 connected to said neck. A movable arm 61 is pivotally anchored at 60 on said cross-member 33 and its free end is adapted for insertion in and for being compressed 70 and held by said bifurcated arm 54 the central portion of said arm 61 being adapted to hold slips 50 and 52 at their corrugated surfaces 51 securely around cable 49, and when loosened to permit of its passing easily between said slips and clamping members. The upper edge 59 of said arm 61 is widened 62 for permitting greater ease of motion of cable 49 above where it passes through said slips 80 50 and 52.

In operation, when the device is in process of being used the clamps at 48 are clamped on the cable 49 in the usual manner after the necessary twist is put in the cable 49, and arm 61 and slips 50 and 52 are left sufficiently loose 85 to permit cable 49 to render through without causing any friction. Drilling then proceeds in the usual manner. When it becomes necessary to let the drilling tools down the driller will loosen handle bar 36 sufficiently 90 to permit the taper bar 13 (which is the so-called screw) to go down the distance desired. Said taper bar 13 is tapered from a larger size 19 at top to the smaller size 20 at the bottom so as to prevent its slipping down, only, as it 95 is permitted to be backed off. The driller will proceed as above until taper bar 13 is down its full length when he will tighten slips 50 and 52 around cable 49 therebetween. He will then loosen slips at 48 permitting the 100 suspending of the drilling tools from clamps 50 and 52. The taper bar 13 will then be carried back to the topmost position in frame 15 by weight 9, acting on elevator rope 8, said rope running through the neck of said frame 105 15 and through pulley 7 in the extreme top of cross-bar, or walking beam 4, and pulley 6 seated on said bar 4, above the Sampson post 1. Pulley 7 is formed so as to prevent the rope 110 from getting out of the groove therein. The weight 9 may vary in size and weight to compensate or off-set the weight of the taper bar 13 and its working parts. The taper bar 13 may be stepped up, step by step, when desired, by the dogs 22 and 23, handle 31 on socket 30. 115 When the above has been completed clamps at 48 may now be tightened, and slips 50 and 52 may now be loosened, and the device be ready for the proceeding with the drilling.

It will be apparent to those familiar with 120 the art to which my invention pertains that continuous drilling will be possible, and will be permitted without the necessity of shutting down to "hitch over" as is now usual.

Having thus described my invention what 125 is claimed and desired to be secured by Letters Patent is:

1. A device of the class described, comprising a frame being adapted for attaching to a standard drilling rig, a bar tapered from 130

- its top to its bottom having steps or teeth, housed in said frame, a weight, elevator rope and pulleys adapted for counter balancing and for aiding in raising and lowering said 50
 5 taper bar, dogs adapted for raising, holding and lowering said taper bar, a first clamping means adapted for gripping said taper bar, head means adapted for rigidly holding a second clamping means securely to said taper 55
 10 bar, a second clamping means adapted to depend from said head means and to grip and hold the line used with said rig and the drilling tools at their lower holding point, a third clamping means anchored adjacent 60
 15 said first clamping means adapted for holding said line in its upper holding position and for permitting said line to render therethrough. 65
2. The combination with a standard oil and gas well drilling rig, and the line and the drilling tools used therewith, of a device of the class described, comprising a frame being adapted for attaching thereto, a bar tapered from its top to its bottom having steps or 70
 25 teeth, housed in said frame, a weight, elevator rope and pulleys adapted for counterbalancing and for aiding in raising and lowering said taper bar, dogs adapted for raising, holding and lowering said taper bar, a first clamping means adapted for gripping said taper bar, head means adapted for rigidly holding a second clamping means securely to said taper bar, a second clamping means adapted to depend from said head means and to grip and hold the line used with said rig and the drilling tools at their lower holding point, a third clamping means anchored adjacent said first clamping means adapted for holding said line in its upper holding position and for permitting said line to render therethrough. 75
 30
 35
 40
3. A device of the class described, comprising a frame being adapted for attaching to a standard oil and gas well drilling rig, and for housing and guiding a taper bar, a taper bar tapered from top to bottom having steps for raising, holding and lowering a 80
 45
- weight, elevator rope and pulleys, adapted for counterbalancing and aiding in raising and lowering said taper bar, a first clamping means attached to said frame adapted for gripping said taper bar, a second clamping means anchored on said frame for gripping the line of said rig at the upper hold thereon and permitting it to render therethrough having inside corrugated gripping surfaces, a head adapted for rigidly holding a third clamping means adapted to depend from said head having inside corrugated 85
 90 gripping surfaces for gripping and holding said line and the drilling tools and permitting said line to render therethrough, dogs adapted for alternately raising and holding step by step said taper bar in said frame.

ORMAN W. DICKERSON.
